(57) **CLAIM**

I claim the ornamental design for a door entry security device, as shown and described.

DESCRIPTION

FIG. 1 illustrates a left frontal perspective view of a door entry security device showing my new design.

FIG. 2 illustrates a frontal view thereof.

FIG. 3 illustrates a rear view thereof.

FIG. 4 Illustrates right view thereof.

FIG. 5 illustrates left view thereof.

FIG. 6 illustrates top view thereof.

FIG. 7 illustrates bottom view thereof; and,

FIG. 8 illustrates right frontal perspective view thereof in the environment of anticipated use.

The broken line showing of a door entry security device is for the purpose of illustrating portions of the article and forms no part of the claimed design. The broken line showing of environmental structure in FIG. 8 forms no part of the claimed design.
